BEAM HANGER

August R. Maier, Dallas, Tex., assignor to Oil
Well Supply Company, Dallas, Tex., a corpora-
tion of New Jersey

Application October 11, 1934, Serial No. 747,975

8 Claims. (Cl. 255—15)

The present invention relates to a hanger to connect pumping apparatus to the end of a reciprocating or walking beam or similar driving mechanism.

Heretofore beam hangers have been used to connect the end of a walking beam to a rod known as the polished rod which passes through a tubing packing and is connected to sucker rods extending to the piston of a pump located at the bottom of a well. The reciprocating or rocking motion of the walking beam is thus transmitted to the pumping mechanism. In its rocking motion the end of the walking beam travels an arc and the upper end of the beam hanger must accordingly be deflected sidewise as the end of the beam passes between the mid-point and either end of its arc of travel. Owing to the great weight of the suspended pumping rods and the liquid being pumped, particularly in very deep wells, it is desirable to avoid as much as possible any deflection of the pull of the beam and its hanger mechanism from the vertical center line of the pump or sucker rod.

It has, therefore, been customary to position the end of the walking beam above the well so that the deflection will not take place entirely to one side, but will be divided equally and thus a maximum deflection of the hanger mechanism will be avoided. It is necessary at times to adjust the stroke of the pump and consequently the swing of the walking beam and, in the constructions heretofore used, this will either lengthen or shorten the part of the arc of travel on one side of the center line of the well, thereby destroying the proper apportionment of the arc and causing a greater deflection of the hanger from the center line of the well than is necessary.

The angle of deflection between the polished rod and the hanger will be greater for a given arc, the shorter the length of the members connecting the beam to the polished rod. The greater the distance from the end of the beam that the hanger is secured to the polished rod, the less will be the angle of pull for any given swing or arc of the walking beam and, accordingly, the less will be the sidewise component of stress. The sidewise stresses will also be lessened by providing maximum of flexibility of swing of the various elements so that no appreciable force required to swing the elements need be added to the sidewise component of stress necessarily imposed by the swinging end of the walking beam.

The objects of the present invention are to provide a beam hanger in which the sidewise stresses on the polished rod may be reduced to

a minimum by providing for the proper adjustment of the hanger relative to the arc traversed by the end of the walking beam, and by providing a connection to the polished rod as far as possible from the end of the beam and to give the apparatus a maximum flexibility. 5

The various features of the invention are illustrated in the accompanying drawings in which—

Fig. 1 is a side view of an end of the walking beam and a hanger embodying a preferred form 10 of my invention.

Fig. 2 is an end view of the apparatus shown in Fig. 1.

Fig. 3 is a top plan view of a lower yoke for connecting the hanger to the polished rod. 15

In my invention the polished rod is connected to the end of the walking beam by means of a connection having a swinging or hinge mounting which may be adjusted in a direction longitudinal to that of the walking beam so that the 20 distance of this connection from the axis of the beam may be readily adjusted in accordance with the amplitude of the rocking of the beam. The mounting of this connection on the beam may be accomplished in any suitable manner as by means 25 of a saddle having a shelflike extension on which the swinging support is slidably mounted and to which it may be secured in any position of adjustment. Accurate adjustment of the position of this mounting may be accomplished by adjusting screws or other equivalent devices. 30

The mounting conveniently will take the form of a shaft and journal, one element of which is secured to the supporting saddle and the other of which is free to swing and from which is suspended a connecting means. This connecting means may be of any suitable form but is most convenient in the form of a pair of straps or rods having a yoke at their lower ends through which passes the polished rod. The yoke is so 40 supported on the rod as to be self-adjusting and to accommodate itself to unevenness in the length of the supporting rods or straps. The polished rod is supported in the yoke by means of a universal support such as a ball and socket joint. 45 With this arrangement the connection of the straps to the polished rod may take place at the lowest possible point on the latter and thereby provide a maximum utilization of the distance between the polished rod and the end of the 50 walking beam for the connecting member.

Referring more particularly to the accompanying drawings, a hanger saddle 10 is mounted on the end of a walking beam 11 being for this purpose preferably provided with hooked or flanged 55

extensions 12 and 13 on the upper and lower surfaces of the beam respectively. A shelflike extension 14 projects outwardly from the saddle 10 and is preferably strengthened by ribs 15. A shaft 5 or journal and bearing assembly 16 is mounted on the shelf 14 to support a pair of downwardly depending metal straps or rods 17 to permit free swinging in the plane of swinging of the beam 11.

The shaft and journal assembly 16 comprises 10 a bearing 18 slidably resting on the upper surface of the shelf 14 and secured thereto in various positions of adjustment by studs 19 extending through suitable slots in the shelf 14 and provided with nuts 20. Adjusting screws 21 pass 15 through upward extensions in the shelf 14 enabling the bearing 18 to be shifted to accurate positions of adjustment, the nuts 20 being loosened before such adjustment and tightened thereafter. A short shaft or journal 22 is journaled in the 20 bearing 18 and extends beyond the ends of the bearing to enable the ends of the straps or rods 17 to pass upwardly through these extending portions and be secured thereto by nuts 23. The straps 17 may also pass through caps 24 on the 25 projecting end of the shaft 22 which are thereby secured and prevent the shaft from becoming displaced. The interior of the bearing 18 is formed into an oil bath chamber 25 which is filled through a lubricant opening 26. The oil 30 seals 27 serve to retain the lubricant in the oil chamber.

It will be apparent from the above construction that the straps or rods 17 swing freely in the manner of a hinge that is maintained well oiled and that the position of this swinging support may be 35 readily adjusted with great accuracy in accordance with any change in the amplitude and, consequently, the shifting of the arc through which the end of the beam swings.

40 The lower ends of the rods or straps 17 support a yoke 28 through which the polished rod 29 or other connection to the pumping mechanism passes and in which it is supported. The mounting of the yoke 28 on the straps 17 is such as to 45 permit the yoke to tilt readily between the straps and accommodate itself to any unevenness in the length thereof and thereby to avoid the necessity for a fine and accurate adjustment of these 50 lengths. For this purpose the ends of the yoke 55 through which the rods 17 pass are provided on their under surfaces with cylindrical recesses, the axes of these recesses being at right angles to the straps or rods 17 and to the plane between these rods. On the end of each rod is mounted a cylindrical seat 30 fitting its respective cylindrical recess in the yoke 28. The seats 30 are secured on the rods 17 by lock nuts 31 or other suitable 60 means. This recess and seat arrangement enables the yoke to tilt in the plane of the rods 17 but not in the plane of swinging of the walking beam 11.

The polished rod 29 passes upwardly through an 65 opening 32 in the yoke 28 midway of the rods 17. The opening 32 is somewhat larger than the diameter of the polished rod 29 to permit a swivel movement between the rod and the yoke. At its 70 upper end the opening 32 is widened to a spherical curvature to receive a support 33 in the form of a spherical segment on which the upper end of the polished rod is mounted by means of a clamp 34. The polished rod is thus secured to the yoke in such a way that it may swing readily in any direction with great freedom and thus avoid any binding that would cause a sidewise stress.

75 The polished rod is prevented from hanging

up on the downstroke by means of a clamp 35 on the polish rod which prevents it from sliding upwardly through the opening 32. The polished rod may be inserted sidewise through the yoke 28 and secured therein by means of a cap or retaining 5 plate 36.

It will be noted that the straps 17 swing between the axis of the shaft 22, which is generally level with the axis of rocking of the beam 11, and the center of the spherical support 33. By positioning the yoke as near as possible to the packing in the tubing the maximum possible length for the rods 17 is thus provided.

What I claim is—

1. A beam hanger comprising a supporting saddle having a sliding surface extending longitudinally thereof, a bearing slidably mounted thereon, means to secure said bearing on said saddle in different positions of adjustment, a shaft journaled in said bearing, and means depending 20 from said shaft to secure a pump rod.

2. A beam hanger comprising a supporting saddle having a sliding surface extending longitudinally thereof, a bearing slidably mounted thereon, adjusting screws to adjust the position of said bearing on said supporting saddle, means to secure said bearing on said saddle in different positions of adjustment, a shaft journaled in said bearing, and means depending from said shaft to 30 secure a pump rod thereto.

3. A beam hanger comprising a supporting saddle having a sliding surface extending longitudinally thereof, a bearing and shaft assembly slidably mounted thereon, securing means for securing said bearing and shaft assembly in different 35 positions of adjustment on said saddle, and connecting means depending from said bearing and shaft assembly.

4. A beam hanger comprising a supporting saddle having a sliding surface extending longitudinally thereof, a bearing and shaft assembly slidably mounted thereon, securing means for securing said bearing and shaft assembly in different 40 positions of adjustment on said saddle, and connecting means depending from said bearing and shaft assembly, said connecting means comprising a pair of straps.

5. A beam hanger comprising a supporting saddle having extensions to hook onto the end of a beam and a shelf portion extending outwardly therefrom, a bearing and shaft assembly mounted on the upper surface of said shelf extension, said shelf having slots therethrough, and studs extending from said bearing and shaft assembly 55 through said slots to secure said bearing and shaft assembly in different positions on said shelf.

6. A beam hanger comprising a supporting saddle having extensions to be secured to the end of a beam and a shelf extending outwardly from 60 the end of said beam, a bearing and shaft assembly mounted on said shelf, said shelf having slots, said bearing and shaft assembly having securing studs extending through said slots, and adjusting screws in said saddle extending to opposite sides of said shaft and bearing assembly to 65 adjust the latter longitudinally of said beam.

7. A beam hanger comprising a supporting saddle having means for securing it to the end of a beam and a shelf extending outwardly from the 70 end of said beam, a bearing and shaft assembly mounted on said shelf extension, means for adjusting the bearing and shaft assembly on said shelf longitudinally of said beam, said bearing and shaft assembly having parts extending past 75

the opposite sides of said shelf, and depending straps extending downwardly from said projecting portions.

8. A beam hanger comprising a supporting saddle having means to attach it to the end of a walking beam and having a shelf extending forwardly from the end of said beam, a bearing on

said shelf, means to adjust the position of said bearing, a shaft in said bearing and projecting beyond the edges of said shelf, and straps mounted on said projecting ends, one at each side of said shelf.

5

AUGUST R. MAIER.
